UNITED STATES PATENT OFFICE.

JOSEPH CHEVALIER SHULTZ AND EUGENE DANIEL SHULTZ, OF BATAVIA,
NEW YORK.

HAT-FASTENER.

SPECIFICATION forming part of Letters Patent No. 738,949, dated September 15, 1903.

Application filed August 11, 1902. Serial No. 119,282. (No model.)

To all whom it may concern:

Be it known that we, JOSEPH CHEVALIER SHULTZ and EUGENE DANIEL SHULTZ, citizens of the United States, residing at Batavia, in the county of Genesee and State of New York, have invented certain new and useful Improvements in Hat-Fasteners; and we do declare the following to be a full, clear, and exact description of the invention, such as will enable others skilled in the art to which it appertains to make and use the same, reference being had to the accompanying drawings, and to the letters and figures of reference marked thereon, which form a part of this specification.

Our invention relates to hat-fasteners; and it has for its object to form a hat-fastener comprising a flat spiral hook or base to engage with the hair of the head and a stem or shank by which the device may be secured to the hat, the shank and spiral being made in one piece and the central portion of the spiral from which the shank extends being formed in a novel manner, so as to impart strength and rigidity at the center of the coil and base of the shank and whereby the hair is prevented from becoming entwined around the shank; and it has furthermore for its object to provide a flexible and preferably absorbent shield for incasing the spiral, which will be compressed to a greater or less extent when the spiral is turned to engage with the hair, and thus afford a firm and at the same time yielding bearing for the hair to be drawn or pressed against in turning the spiral, so that the hat will be held more firmly in place on the head, and when made of absorbent material the shield will absorb moisture that may form on or attach to the spiral, and thus prevent oxidation of the spiral.

To the accomplishment of the foregoing and such other objects as may hereinafter appear, the invention consists in the construction and in the combination of parts herein-after particularly described and then sought to be clearly defined by the claims, reference being had to the accompanying drawings, forming a part hereof, and in which—

Figure 1 is a perspective of our device with the binding-nut and jam-nut separated from

the shank of the spiral; Fig. 2, a vertical cross-section through the fastener, showing the manner of attaching it to a hat. Fig. 3 is a face view of the spiral with the shield in vertical section, and Fig. 4 is a view looking at the front of the fastener with the binding-nut and jam-nut omitted.

In the drawings the numeral 1 designates a flat spiral or coil, the convolutions of which lie in substantially the same plane, so that when the free end 2 of the spiral engages the hair and the spiral is turned the hair will be drawn in a direction substantially in the same plane with the coils of the flat spiral. The shank 3 and the flat spiral are made from a single piece of suitable wire, and for the purpose of imparting rigidity and firmness to the center of the spiral and to afford a rigid base for the shank 3 we deflect or bend the wire at the base of the shank 3 at right angles to the length of the shank, as shown at *a*, and then bend the wire backwardly in a circle concentric to the shank, as shown at *b*, bringing the wire against the right-angle bend *a*, as shown, and then bend the wire in a reverse direction, forming a loop *c* next to the bend *a* and continuing the wire in concentric convolutions, so as to form the spiral, as illustrated clearly in Fig. 3 of the drawings. This will afford or make a stiff and rigid center to the spiral and base to the shank and will also prevent the hair from entwining around the shank, because in the turning of the spiral the hair cannot pass nearer to the shank than the base of the loop *c*, and consequently the hair will be prevented from passing between the part *a* and the loop *c* and from entwining around the shank, and thus it is impossible for the hair to become entwined around the shank or caught and held at any point, which, if permitted, would interfere with the release of the fastener when necessary. The outer portion of the shank 3 is screw-threaded, as illustrated, so as to receive a binding nut or knob 4, which may be of any desired configuration, and the shank also receives a jam-nut 5, so that the fastener may be secured to the hat-body and yet be free to rotate in fastening and unfastening the hat to the head.

For the purpose of insuring the hat being held firmly on the head we provide the flat spiral 1 with a flexible shield or casing 6, made of chamois, cloth, or other flexible material. By providing the spiral with such a shield when the spiral is turned for the purpose of engaging and entwining therewith the hair of the head the pressure or drawing action of the spiral on the strands of hair will compress or contract to a greater or less extent the flexible shield, and thus the shield will be caused to afford a firm and yet yielding bearing toward and against which the hair will be drawn. This will cause the hat to be held more firmly on the head than would be the case if the thickness of the hair alone were depended upon to afford a bearing for the spiral. It is preferred to employ for this flexible shield some suitable material possessing absorbent qualities to a greater or less extent, so that the shield will take up any moisture that might otherwise form on or adhere to the spiral and cause oxidation to a greater or less extent. In actual practice the free end of the spiral will be bent outwardly and downwardly about one-half inch, more or less, so that the free end may grasp quite a lock of the hair, which by one turn of the spiral will be drawn into the spiral and tightly compressed in the narrow space between the coils.

We have described with particularity the details of construction as well as the function of the several parts of our hat-fastener; but it is obvious that changes can be made in the same and essential features of our invention be retained.

Having described our invention and set forth its merits, what we claim is—

1. A hat-fastener consisting of a shank and a flat spiral at the base thereof, the material of which the shank and spiral are formed being bent at right angles to the length of the shank, and then bent concentrically to the shank and then bent in a reverse direction to form a loop whose fold is next to the right-angle bend, the material then being continued to form concentric coils, substantially as described.

2. A hat-fastener comprising a flat spiral and a shank, the material forming the two being bent at right angles to the shank and then concentrically to the shank and then bent reversely to form a loop next to the right-angle bend and then continued in concentric coils, a threaded binding-nut applied to the shank, and a jam-nut between said nut and the spiral, substantially as described.

3. A hat-fastener consisting of a spiral having a shank extending therefrom, and a flexible shield or casing applied to the spiral, substantially as described.

4. A hat-fastener consisting of a spiral having a shank extending therefrom and an absorbent shield applied to the spiral, substantially as described.

In testimony whereof we affix our signatures in presence of two witnesses.

JOSEPH CHEVALIER SHULTZ.
EUGENE DANIEL SHULTZ.
